UNITED STATES PATENT OFFICE.

JOHN GOWDEY, OF PHILADELPHIA, PENNSYLVANIA.

DESIGN FOR A BOOK END OR SIMILAR ARTICLE OF MANUFACTURE.

Application filed November 16, 1928. Serial No. 28,913. Term of patent 14 years.

To all whom it may concern:

Be it known that I, JOHN GOWDEY, a citizen of the United States, residing in Philadelphia, Pennsylvania, have invented a certain new, original, and ornamental Design for a Book End or Similar Article of Manufacture, of which the following is a specification, reference being had to the accompanying drawing, forming part thereof, in which:

Figure 1 is a face view of a book end, or similar article of manufacture illustrating my new design;

I claim:

The ornamental design for a book end or similar article of manufacture, substantially as shown.

JOHN GOWDEY.
